UNITED STATES PATENT OFFICE

JOSEPH WIESER, OF ST. JOHNSVILLE, NEW YORK, ASSIGNOR TO F. ENGELHARDT & SONS, OF ST. JOHNSVILLE, NEW YORK, A FIRM.

XYLOPHONE ATTACHMENT FOR PIANOS.

932,212.

Specification of Letters Patent. Patented Aug. 24, 1909.

Application filed February 24, 1909. Serial No. 479,749.

To all whom it may concern:

Be it known that I, JOSEPH WIESER, a citizen of the United States, residing at St. Johnsville, Montgomery county, State of New York, have invented new and useful Improvements in Xylophone Attachments for Pianos, of which the following is a specification.

This invention relates to a xylophone attachment for pianos, which is tuned in unison with the lower treble strings and serves to emphasize the melody played on the piano. The xylophone beaters are operated by pneumatic means in such a manner that they will be actuated simultaneously with the corresponding piano hammers, so that one and the same impulse will suffice for operating a piano hammer and its corresponding xylophone beater.

In the accompanying drawings: Figure 1 is a front view of the upper portion of a piano provided with my improved xylophone attachment, the piano action proper being omitted; Fig. 2 a vertical cross section on line 2—2, Fig. 1, showing the piano action; Fig. 3 an enlarged vertical section through the xylophone attachment, on line 3—3, Fig. 1; Fig. 4 a front view of one of the pneumatics operating the xylophone beaters. Fig. 5 a cross section on line 5—5, Fig. 4; Fig. 6 a vertical longitudinal section on line 6—6, Fig. 3, drawn on a reduced scale; Fig. 7 a vertical section on line 7—7, Fig. 1; Fig. 8 a vertical section on line 8—8, Fig. 1; Fig. 9 an enlarged vertical section on line 9—9 Fig. 7; Fig. 10 a face view of the regulating valve, and Fig. 11 a side view, partly in section, of modified means for actuating the xylophone.

The numeral 15 indicates the case of an autopneumatic piano, said case inclosing strings 16, hammers 17, abstracts 18, capstans 19 and keys 20, all as usual. Keys 20 are adapted to be operated through lifters 21 from the action pneumatics, (not shown), but may also be operated manually. In order to accentuate the tune or melody of the piece played, a xylophone 22 is mounted in front of strings 16, the wooden bars 22^a, of which are tuned in unison with the lower set of the treble piano strings. The construction is such that the beaters 23 of the xylophone are operated simultaneously with the corresponding piano hammers 17. For this purpose there is mounted upon each of those

keys 20 which are adapted to sound the xylophone, an auxiliary capstan 24 placed in front of capstan 19. Capstan 24, when raised by the depression of its key, operates pneumatic means for actuating beaters 23. These means consist of a longitudinal bar 25 mounted in case 15 at a distance above keys 20 and extending across the same. Bar 25 is, by arms 26, connected to a rail 27 supported by standards 28 upon the key board 29. Bar 25 is provided with a row of perforations or ports 30, the number of which corresponds to the number of xylophone beaters 23. The perforations 30 are normally closed at their bottom through air inlet valves 31 which are pivoted to flanges 32 depending from rail 27. The padded rear arm of each lever 31 is arranged above one of the capstans 24, so that upon the ascent of such capstan, the front arm of lever 31 is withdrawn from bar 25 to open its port 30. Each port 30 is connected by a tube 33 to a duct 34 formed below the diaphragm 35 of a primary valve which is composed of a stem 36, an upper valve disk 37 and a lower valve disk 38, stem 36 being supported upon diaphragm 35. The primary valves are arranged within a lower valve block 39 mounted within casing 15 above bar 25. Disk 38 plays within a vacuum chamber 40 and controls communication between said chamber and a duct 41, while disk 37 controls communication between said duct and the atmosphere. Duct 41 is by tube 42 connected to a passage 43 formed below the diaphragm 44 of a secondary valve arranged within an upper valve block 45 located above block 39. Each secondary valve comprises a stem 46 resting upon diaphragm 44, a lower valve disk 47 controlling communication between a vacuum chamber 48 and a duct 49, and an upper valve disk 50 controlling communication between said duct and the atmosphere. Duct 49 is, by a tube 51, connected to the interior of a pneumatic or bellows 52 arranged above valve block 45. To the movable board of pneumatic 52 is connected, by a flexible strap 53, the shank 54 of beater 23. Shank 54 is guided within a padded slot 55 formed in a bar 56 which is secured to the movable board of pneumatic 52.

Vacuum chambers 40, 48 are, by longitudinal ducts 57, 58, respectively, connected to a vertical transverse duct 59 formed within a

head 60 connecting blocks 39 and 45. From duct 59 there leads a tube 61 to an inclined duct 62 controlled by a rotary valve plug 63 operable by a handle 64 carried by the head 5 65 of the plug. Duct 62 is, by duct 66, adapted to communicate with a tube 67 which leads to the main vacuum bellows, (not shown).

The operation is as follows: Upon the depression of one of the lower treble keys 20, capstans 19 and 24 are raised. The ascent of capstan 19 will cause the corresponding piano hammer 17 to strike its string, while beater 23 of the xylophone attachment is 10 actuated in the following manner: By raising capstan 24, lever 31 is tilted to swing its forward end off bar 25 and thus admit air into port 30. As the air is continuously withdrawn from chamber 40 through ducts 20 57, 59, tube 61, duct 62, open valve 63, duct 66 and tube 67, the opening of port 30 will cause diaphragm 35 to ascend, thereby closing valve 38 and opening valve 37. Air will thus be admitted through duct 41, tube 25 42 and duct 43, below diaphragm 44. The air being constantly withdrawn from chamber 48 through duct 58, diaphragm 44 will ascend to close valve 50 and open valve 47. Air will thus be withdrawn from pneumatic 30 52 through duct 49 and tube 51, to cause a collapse of the pneumatic and a corresponding throw of beater 23 against a bar 22^a of the xylophone 22. As the beater-shank 54 is yieldingly connected to the movable board 35 of pneumatic 52, beater 23 will rebound, after striking its bar, to produce a pure note. When key 20 is released, port 30 is closed by lever 31, whereupon the air is withdrawn from duct 34 through passage 68 and a bleed- 40 hole 69, to cause a descent of the primary valve. In this way valve 37 will be closed, while valve 38 is opened to connect vacuum chamber 40 with duct 43. Owing to the withdrawal of the air from duct 43, diaphragm 44 will descend to close valve 47 and open valve 50. Air will thus be admitted through open valve 50, duct 49 and tube 51, into pneumatic 52, so that the latter will be expanded by a spring 70.

50 By properly adjusting valve 63, the suction within pneumatics 52 and consequently

the force of the beater-stroke may be regulated, so as to render the xylophone accompaniment more or less impressive. By closing valve 63, the xylophone attachment may 55 be completely silenced, as will be readily understood.

In Fig. 11, modified means for operating the xylophone attachment are illustrated. This modification is intended to be used with 60 those pianos in which the lifter 71, operated by the action pneumatic, (not shown), does not influence the piano key, but actuates the abstract 18 directly. As shown, a cushioned screw 72 is tapped into an arm 73 projecting 65 forwardly from the abstract, said screw engaging the rear arm of lever 31.

It will be seen that by the means described, the melody played on the piano is emphasized and more effectively brought out by 70 the xylophone, so that the instrument is more particularly adapted for use in ball rooms, skating rinks and other large places of entertainment. As the xylophone beaters are actuated by the same lifters that 75 operate the piano hammers, the conventional tune sheets adapted to operate a piano may be utilized without change, for playing my instrument.

I claim:

1. A musical instrument comprising a series of piano hammers, a series of keys, a perforated bar extending across the keys, valves actuated by the keys and controlling the bar-perforations, a series of xylophone beaters, 85 and pneumatic actuating means intermediate the perforated bar and said beaters.

2. A musical instrument comprising a series of piano hammers, a series of keys, a perforated bar extending across the keys, lever-valves controlling the bar-perforations, capstans on the keys engaging the lever-valves, 90 a series of xylophone beaters, and pneumatic actuating means intermediate the perforated bar and said beaters.

Signed by me at St. Johnsville, N. Y., this 95
20th day of February, 1909.

JOSEPH WIESER.
